UNITED STATES PATENT OFFICE.

HENRY J. VIGNEAULT, OF WORCESTER, MASSACHUSETTS, ASSIGNOR OF ONE-HALF TO
GEORGE N. VIGNEAULT, OF WORCESTER, MASSACHUSETTS.

COLLAR.

1,407,342.

Specification of Letters Patent. Patented Feb. 21, 1922.

Application filed December 29, 1920. Serial No. 433,761.

To all whom it may concern:

Be it known that I, HENRY J. VIGNEAULT, a citizen of the United States, residing at Worcester, in the county of Worcester and 5 State of Massachusetts, have invented a new and useful Collar, of which the following is a specification.

This invention relates to a collar for personal wear and the principal object 10 thereof is to provide an integral device thereon for attaching it to the shirt without the use of a collar button in the rear, thus permitting of the elimination of the rear button hole and collar button and saving 15 in the expense of manufacture of the collar as well as reducing the difficulties in its use.

Reference is to be had to the accompanying drawing in which—

20 Fig. 1 is a plan of a blank for a soft collar showing a preferred form of this invention;

Fig. 2 is a plan of the complete collar 25 opened out flat, and

Fig. 3 is an enlarged central sectional view on the line 3—3 of Fig. 2.

Ordinarily collars are provided with a rear button hole for attachment to the rear of the shirt band by means of a stud. This 30 button hole involves some expense in manufacture not only for the actual cutting and sewing around it but on account of the fact that it is responsible for a large percentage of the imperfections in the collar and therefore 35 a corresponding proportion of the waste. Furthermore, the studs are a nuisance to the wearer, catching into the necktie and making it difficult to adjust and frequently getting lost or misplaced. One particular 40 disadvantage lies in the fact that no matter how short the shank of the stud is it forms a projection bearing on the top of the vertebræ of the wearer. This exerts a considerable degree of pressure at that 45 point thus causing discomfort and sometimes even more serious trouble. By this invention these difficulties are avoided.

This collar is intended to be worn with the well-known types of shirt in which the 50 neck band is provided with a pocket formed by the turning down of the edge of the neck band all around and sewing it down to the neck band by two vertical seams thus providing a downwardly opening pocket between 55 the seams. The tab is intended to be

about as wide at its widest place as this pocket is, and about as high as the band of the shirt.

The collar is applied very simply by bringing it around into proper position and directing the tab piece into the pocket above described. When once located in the pocket it will not move circumferentially to any great extent although it is capable of slight motion in that direction. The collar cannot move outwardly and the only direction in which it can move is downwardly to disconnect it from the shirt band. This, however, is prevented as soon as the collar is brought around to the front and buttoned in the front in the usual manner. It will be seen therefore that the collar is held firmly in position and cannot be dislodged without unbuttoning it at the front, at least on one side. When once put into place it will stay there as if buttoned in the pocket.

I have shown the application of the invention to a soft collar. In making it the blank is made by sewing together two pieces of linen wrong side out as indicated in Fig. 1. 80 These are each provided with a tab 11. They are sewed together along the bottom by a line of stitching 37, but a piece of cloth 31 is sewed between them. The upper edge of this is formed along the selvage of the cloth 85 so that it will be strong. Now the blank is turned inside out sewed again all around, and the button holes at the ends cut and worked. This leaves the piece 31 on the front with a pocket behind it, open at the 90 top, and having a strong selvage upper edge. Into this I place a piece 38 of celluloid, paste board, or other stiff sheet material to fill the pocket and render it stiff. In use this is turned up as in Fig. 3.

A collar made in this way has several advantages. In the first place no button hole has to be provided in the back. This cheapens the cost of manufacture, reduces the number of defective collars made, and also 100 increases the life of the collar because occasionally these rear button holes tear out. As described above the collar is very easily applied and will stay in position indefinitely after it has been applied and buttoned in the 105 front. A very important feature consists in the fact that there is no projection at the rear thicker than the thickness of the collar itself, bearing on the back bone of the wearer. Thus, a source of irritation, and 110

sometimes disease, is removed. Also by this device the slipping of the tie around the collar is more easily accomplished. Furthermore, there is no collar button to lose which is an important advantage. When these collars are used commonly enough the rear button hole in the neck band of the shirt can be omitted also.

Although I have illustrated and described 10 only a single form of the invention I am aware of the fact that modifications can be made therein by any person skilled in the art without departing from the scope of the invention as expressed in the claims. Therefore, I do not wish to be limited to all the 15 details of construction or the particular type of collar herein shown and described but what I do claim is:—

1. As an article of manufacture, a soft

collar having an upward projection at the 20 bottom of the collar band for attachment to a shirt having a piece of cloth sewed to it around the edge with its selvage along the bottom of the collar and free therefrom to constitute a pocket, and a stiffening piece re- 25 movably located in the pocket.

2. As an article of manufacture, a soft collar having an upwardly projecting integral tab constituting the sole means for attaching it to the rear of a shirt neck band, 30 and a continuous line of stitching along the bottom of the collar and the edge of said tab, a piece of cloth sewed to the tab by said line of stitching constituting a pocket, and a piece of sheet material in said pocket. 35

In testimony whereof I have hereunto affixed my signature.

HENRY J. VIGNEAULT.
